UNITED STATES PATENT OFFICE.

BENJAMIN W. JONES, OF SCHENECTADY, NEW YORK, ASSIGNOR TO GENERAL ELECTRIC COMPANY, A CORPORATION OF NEW YORK.

THERMOELECTRICAL TIMING CONTROL.

Application filed August 13, 1923. Serial No. 657,253.

This invention relates to an electric circuit control system embodying an automatic thermo-electrical timing device for controlling the alternate connection of a translating circuit to a supply source and its disconnection therefrom at recurring intervals. The invention is particularly adapted for periodically flashing on and off the electric lamps of an illuminated advertising sign, 10 although the invention is not necessarily limited in its application to a sign flashing control.

One of the objects of my invention is to provide an improved control arrangement 15 in such a system which is simple in construction, reliable in operation, and which may be manufactured and installed with minimum expense.

Another object of my invention is to provide an automatic timing control for a translating circuit capable of safely and effectually handling relatively large currents and which is positively governed by a thermo-electrical timing device of low current 25 interrupting capacity, having time intervals of heating and cooling independent of the current in the translating circuit, and provided with means for independently regulating the time intervals.

The novel features which I believe to be characteristic of my invention are set forth in the appended claims. My invention itself, however, both as to its organization and method of operation will best be understood by reference to the following description taken in connection with the accompanying drawing which shows diagrammatically the application of my invention to sign flashing control.

As illustrated in the drawing my improved control is embodied in a sign flashing system in which the translating circuit includes the lamps 9, which may be arranged in any desired number and manner 40 to form an illuminated sign. The lamps are supplied with current from supply mains 10 and 11 which may be the usual lighting power mains.

An electromagnetic switch 12, of the throw-over type, is provided with cooperating contacts 13 and 14, which are suitably designed to open and close the circuit of the lamps 9 composing the sign. Movable contact 14, is carried by switch member 15 55 which is operable from the open position

shown to its closed position in which engagement is made between movable contact 14 and stationary contact 13. The switch member 15 is pivotally mounted in the stationary support 16 and is biased to the position to which it is last operated by means of the over-center device comprising spring 17 which surrounds pin 18, one end of which passes through an aperture in the stationary support and the other end of which is pivotally connected to switch member 15. Movable contact 14 is of the follow-up type so designed as to make and break engagement with stationary contact 13 when switch member 15 is passing through the dead center position of the over-center biasing device. The electromagnetic switch 12 is provided with a plunger or armature 19 which is pivotally connected at one end with switch member 15 and cooperates with two operating windings 20 and 21, the former of which when energized acts upon the armature 19 to move the switch to closed position and the latter when energized likewise acts upon the armature 19 to move the switch to open position. The actuation of switch 22 to either open or closed position is accomplished by a momentary energization of the proper operating winding.

A thermo-electrical timing device 22 is provided for automatically effecting the alternate energization of the switch operating windings 20 and 21 and comprises a bimetallic thermal responsive element 23 such as is commonly used in thermostats, and a suitable electrical heater 25. The thermal responsive element 23 is fixed at its lower end in stationary base member 24 and has its central portion closely surrounded by the electric heater 25. The element 23 carries near its upper end a pair of contacts one of which is adapted to engage with the contact 26 when the element flexes to the right into its cool position, and the other of which engages contact 27 when the heater circuit is energized and causes the thermal responsive element to flex to the left into its hot position.

Contacts 26 and 27 are individually adjustable to the right or left as shown in order that the time intervals of heating and cooling of timing device 22 may be regulated to vary the time "on" and "off" of the translating circuit. In this connection it will be understood that the rate of heating

of timing device 22 depends jointly upon the heating capacity of coil 25 and the heat dissipation facilities of the timing device, and that the rate of cooling depends primarily upon the heat dissipation alone. The heating capacity of coil 25 is preferably fixed although suitable means may be provided for varying the current in the coil and correspondingly varying the heating capacity, for example, a variable resistance. But the rate of heat dissipation is always a function of the difference between the temperature of the device and that of the surrounding medium. Hence, by moving both contacts 26 and 27 to the left the thermal element 23 is operated at a higher temperature and the time of heating of the timing device 22 is increased and the time of cooling decreased. Adjustment to the right produces the reverse effect. Furthermore, it will be evident that increasing or decreasing the gap between contacts 26 and 27 increases or decreases both the time of heating and cooling. Thus by proper adjustment of contacts 26 and 27 the operation of timing device 22 may be varied to give a wide range of time intervals.

The operation of my invention is as follows: With the supply lines 10 and 11 energized from a suitable source and the several controlling elements in the position shown in the drawing the lamps 9 are dark since the sign circuit is open at contacts 13 and 14 and the timing device 22 is cooling down as the heater circuit, including heating coil 25, is likewise open. Assume that the time required for the timing device to cool has elapsed, and that thermal responsive element 23 has flexed to the right into engagement with contact 26. A circuit for the closing winding 20 of switch 12 is thereby completed from the supply conductor 11 through the winding 20, contact 26, thermostat 23, base 24, lamps 9 and heater 25 in parallel circuit to the other supply conductor 10. The current flowing in this circuit is relatively small due to the resistance of coil 20 and hence it is not sufficient to light lamps 9. The energization of closing winding 20 of switch 12 causes armature 19 to move switch member 15 against the strain of the spring 17 until it has passed the dead center position of the toggle mechanism whereupon spring 17 assists in snapping movable contact 14 on switch member 15 into a quick wiping engagement with stationary contact 13.

It will be observed that three circuits are controlled by the operation of switch 12, one being the translating circuit including the sign lamps 9 which is completed as follows:—from supply conductor 11 through a flexible connection to switch member 15, through contacts 14 and 13, lamps 9 to the other supply conductor 10, the second being

the heater circuit including heater 25 which may be traced as follows: from the supply conductor 11 through a flexible connection to switch member 15, through contacts 14 and 13, heater 25, to the other supply conductor 10, and the third being the energizing circuit of winding 20 or 21 depending upon whether switch 12 is operated to closed or open position respectively. 70

Upon the operation of switch 12 to closed position, the engagement of contacts 13 and 14 completes the translating circuit to flash lamps 9 from the source, short circuits winding 20, and energizes the heater 25 which at once begins to heat up timing device 22. As 75 the timing device is heated thermal responsive element 23 draws away from stationary contact 26 and flexes toward stationary contact 27, thereby opening the circuit of closing coil 20 of switch 12. However, 80 spring 17 continues to maintain contacts 13 and 14 in firm engagement until the predetermined time required for the element 23 to complete its flexure towards contact 27 has elapsed. It should be noted that when 85 the element 23 leaves stationary contact 26 no arcing can occur due to the fact that winding 20 has been short circuited by the prior engagement of contacts 14 and 13. Upon the engagement of element 23 with 90 stationary contact 27, a circuit for opening coil 21 of switch 12 is completed from the supply conductor 11 through switch member 15, contacts 13 and 14, base 24, thermostat 23, contact 27, and through winding 21 100 to the other supply conductor 10. The energization of winding 21 causes armature 19 to quickly move switch member 15 past the dead center position into open position and thereby interrupt the sign circuit and 105 darken the lamps 9. The operation of switch 12 to open position also opens the energizing circuit of winding 21 and interrupts the circuit of heater 25 thus permitting the timing device 22 to cool. As the 110 timing device cools thermal responsive element 23 leaves stationary contact 27 and again flexes toward stationary contact 26. Again no arcing can occur upon the disengagement of element 23 from stationary contact 27 since the circuit of winding 21 has 115 been interrupted by the previous opening of switch 12. After a predetermined interval of cooling the engagement of contact 26 by thermal member 23 will be effected 120 and the cycle of operations just described will be repeated continuously and indefinitely. 125

The periodicity at which the sign is flashed is practically constant and is not affected by variations in the amount of current consumed in the sign since the heater circuit of the thermo-electrical timing element is connected to receive energy from the line independently of the translating 130

circuit including the sign lamps. It will be understood that suitable switches for initiating and terminating the operation of the sign flasher may be placed either in the supply mains 10 and 11 or in the conductors leading therefrom and may be arranged for manual operation or operation by a time clock as desired. Also a plurality of my controls may be used to control different groups of lamps in a sign thus producing a most attractive illuminating effect.

In accordance with the provisions of the patent statutes, I have described the principle of operation of my invention, together with the apparatus which I now consider to represent the best embodiment thereof, but I desire to have it understood that the apparatus shown is only illustrative and that the invention can be carried out by other means.

What I claim as new and desire to secure by Letters Patent of the United States is:—

1. A thermo-electrical timing control for a translating circuit, comprising an electromagnetic switch for controlling said circuit, said switch having only one circuit-closing position and only one circuit-opening position, and provided with mechanism for biasing said switch to each of said positions when operated thereto, a thermo-electrical timing device operable between two circuit-closing positions, for controlling the successive closure and opening of said switch, and connections whereby the said timing device is successively heated and permitted to cool in accordance with the operation of said switch between said circuit-closing and circuit-opening positions.

2. A thermo-electrical timing control for a translating circuit, comprising an electromagnetic switch for controlling said circuit, said switch having only one circuit-closing position and only one circuit-opening position, a thermo-electrical timing device having a heating element connected in multiple relation with the translating circuit to provide a predetermined time of operation of the device between two circuit-closing positions independently of the value of the current flow in the translating circuit, and connections whereby the said switch is energized to successively open and close said translating circuit in accordance with the operation of said timing device and the said timing device is successively heated when said electromagnetic switch is operated to said circuit-closing position and permitted to cool when said electromagnetic switch is operated to said circuit-opening position.

3. A thermo-electrical timing control for a translating circuit, comprising an electromagnetic switch for controlling said circuit, a thermo-electrical timing device under the control of said switch and operable with a time delay between two circuit-closing po-

sitions independently of the current in the translating circuit controlled by said electromagnetic switch, means for independently varying the time of operation of said device from either position to the other, and connections whereby the said electromagnetic switch is electromagnetically operated between a circuit-closing position and a circuit-opening position in accordance with the operation of said timing device between its circuit-closing positions.

4. A thermo-electrical timing control for a translating circuit, comprising an electromagnetic switch for controlling said circuit, said switch having only one circuit-closing position and only one circuit-opening position, a thermal responsive element having a predetermined time of operation between two circuit-closing positions, an electrical heater circuit for said element arranged to be energized independently of the current in the translating circuit, and connections whereby the said electromagnetic switch is successively energized to close and open said translating circuit and said heater circuit in accordance with the operation of said timing device between its circuit-closing positions.

5. A thermo-electrical timing control for a translating circuit, comprising an electromagnetic switch for controlling said circuit, said switch having only one circuit-closing position and only one circuit-opening position, and having an operating winding for electromagnetically operating the switch to each position, mechanism for biasing said switch to each of said positions upon operation thereto, a thermo-electrical timing device operable between two circuit-closing positions for successively energizing said windings and having a heating element connected in multiple relation with the translating circuit to render the operation thereof independent of the value of current flow in said circuit, and connections whereby said windings are successively deenergized and the timing device is successively heated and permitted to cool in accordance with the operation of said electromagnetic switch between said circuit-closing position and said circuit-opening position.

6. A thermo-electrical timing control for a translating circuit comprising an electromagnetic switch for controlling the said circuit and having a closing winding and an opening winding, a thermo-electrical timing device operable between two circuit-closing positions for successively energizing said windings, and connections whereby said closing winding is short circuited and the energizing circuit of said opening winding is opened and the timing device is successively heated and permitted to cool in accordance with the operation of said electromagnetic switch between a circuit-closing and a circuit-opening position.

7. A thermo-electrical control for flashing a translating circuit from a source of current, comprising an electromagnetic switch for flashing said circuit, said switch having
5 only one circuit-closing position and only one circuit opening position and said switch having a closing and an opening winding and being provided with mechanism whereby the switch is biased to the position to which
10 it was last operated, a thermo-electrical timing device comprising a circuit controlling thermal element having an independently adjustable time of operation to hot and cool circuit controlling positions respectively, and
15 an electrical heater coil therefor connected in parallel circuit with said translating circuit, and connections whereby the thermal

element when in its cool position energizes said switch closing winding in series circuit with the translating circuit to operate said switch to simultaneously close said translating circuit, short circuit said closing winding, and connect said heater coil to heat said thermal element and when in its hot position energizes said switch opening winding to operate said switch to simultaneously open said translating circuit, open the energizing circuit of said opening winding, and disconnect said heater coil to permit said thermal element to cool.

In witness whereof, I hereunto set my hand this 11th day of August, 1923.

BENJAMIN W. JONES.
